UNITED STATES PATENT OFFICE

JOSEPH E. FARRELL, JR., OF WASHINGTON, DISTRICT OF COLUMBIA

BATTERY TERMINAL CONNECTER

Application filed March 22, 1928. Serial No. 263,840.

This invention relates to battery terminal connectors, and more particularly to a novel construction for facilitating the quick detachment of the connector from the battery terminal.

The difficulty in disconnecting wire terminals of the type now generally used from automobile and radio battery terminals is well known, the operation frequently requiring the use of a terminal "puller" or several hammer blows which injure the battery terminal and also prove annoying and expensive on account of the time consumed.

Accordingly, the present invention has primarily in view a novel construction consisting of a few substantial parts which may be economically manufactured and assembled, and when in use will permit of disconnecting the wire terminal from the battery terminal by the ordinary pressure exerted from the operator's finger grip, or, if desired with the use of the tool, though that has been found to be seldom necessary. In that connection the invention aims to provide a construction which will completely house and protect the battery terminal, thereby minimizing the effect of corrosion and insuring a firm and positive engagement between the wire terminal and the battery terminal which will improve the charging and discharging of the battery due to the lowering of resistance which otherwise results from a poor connection.

A further object of the invention is to provide a construction which includes a part having an interiorly tapered wall, the taper being inwardly and downwardly, that is, converging toward the base of the battery terminal, and adapted to cooperate with terminal gripping elements in such a way that the manipulation of the releasing means will relieve the wedging engagement between the gripping elements and the member having the interior taper so that if necessary the latter may be subjected to a slight tap downwardly which will cause the inner faces of the battery gripping elements to disengage the battery terminal in event that it should happen to stick.

With the above and other objects in view

which will more readily appear as the nature of the invention is better understood, the same consists in the novel construction, combination and arrangement of parts herein-after more fully described, illustrated and claimed.

A preferred and practical embodiment of the invention is shown in the accompanying drawings in which

Figure 1 is an elevation of the improved construction.

Figure 2 is a vertical sectional view thereof.

Figure 3 is a view similar to Fig. 2 showing the battery terminal gripping elements released from engagement with the battery terminal.

Figure 4 is a bottom plan view.

Figure 5 is a detail perspective view of one of the segmental gripping elements.

Similar reference characters designate corresponding parts throughout the several figures of the drawings.

In carrying the invention into effect it is proposed to provide a wire carrying member or sleeve designated generally as A and carrying therewith the wire B while the interior thereof is provided with the gripping elements designated generally as C for engaging with the battery terminal D when manipulated by the actuator or cap E in the manner to be presently referred to more in detail.

The sleeve A is preferably of hollow formation and is provided with an inverted frusto-conical interior wall 1, that is to say, a wall which is tapered inwardly and downwardly toward the base of the battery terminal D, thereby distinguishing from battery terminal connectors which have a wall tapered in the opposite direction, and which is objectionable because efforts to remove the terminal by tapping only serve to wedge the gripping elements more tightly together. As previously indicated the present invention is constructed with the primary view that a minimum amount of force will be required to disconnect the entire device from the battery terminal, yet on the other hand, the device has been constructed with a view

to being able to efficiently function in the event that the parts to be disconnected have for any reason become "frozen" to each other. The interior of the sleeve A is further provided at the wide end of the wall 1 with an exteriorly tapered portion 2 which is adapted to receive the externally threaded periphery 3 of the gripping element actuator or cap E. For the purpose of facilitating the manipulation of the cap E the same is provided with an offset head 4 which is adapted to receive a transverse cross key 5 to render finger manipulation more comfortable, though it will of course be understood that the head 4 may be formed with angular faces to cooperate with a wrench or other tool.

The gripping elements or jaws C for engaging the battery terminal D are preferably of segmental formation and each comprise a body 6 having an outer tapered face 7 for engaging with the inwardly and downwardly inclined tapered wall 1 of the casing, and the vertical or substantially vertical inner battery terminal engaging face 8. The upper end of the body 6 may be slotted or otherwise suitably formed to provide a shoulder 9 adapted to be engaged by the head 10 of a gripping element supporting stud 30 mounted on the inside face of the cap E. The effect of the engagement of the shoulders 9 with the head 10 is to hold the segments in abutting relation with the underside of the cap so that when the same is screwed downwardly into the casing the full force of the screw cap will be delivered to the segments thereby to cause the inclined faces 7 thereof to engage the interior inwardly and downwardly tapering wall and thus force the faces 8 into firm binding contact with the binding terminal D. On the other hand when it is desired to remove the connector from the battery terminal the unscrewing of the cap E will cause the head 10 to work against the shoulder 9 to thus effect a relative movement between the segments C and the casing A. There is sufficient tolerance or play provided between the underside of the head 10 and the shoulder 9 of the inwardly directed flange 9a to permit of the cap being moved a slight distance before the under side of the head engages the shoulder 9. For example this tolerance or clearance may be sufficient to permit the cap to turn a quarter or half turn, thereby relieving the under side of the cap from pressure engagement with the upper side of the inwardly directed flange 9a so that continued movement of the cap under hand pressure will cause the under side of the head to engage the shoulder 9 to move the segments sufficiently to break the engagement between the inclined faces 7 of the segments C and the interior tapered bore 1 of the casing. If 65 after the initial movement of the cap it is

difficult to continue the turning movement of the cap by finger pressure, the top of the cap may be struck a light blow or in other words may be tapped which will have the effect of pushing the sleeve A downward since the segments are still resting on the battery terminal, this downward movement being possible due to the play between the under side of the head 10 and the shoulder 9 of the inwardly directed flange 9a. The continued turning movement of the cap E will continue to move the sleeve A downward until sufficient space is provided between the inner side faces of the jaws and the interior tapered bore of the sleeve to permit easy removal of the connector from the battery terminal D. It will, therefore, be apparent that the space or distance between the inner side of the head 10 and the under side of the cap 11 is normally greater than the thickness of the inwardly directed flange 9a.

Another distinctive feature of the invention resides in the provision of the gripping segments C which move radially with reference to the axis of the battery terminal D. The battery terminals are usually of lead or a soft composition, and due to the fact that the segments are firmly driven into contact with the soft metal of the terminal, the latter will key into the space between the segments when they are pressed or driven inwardly under the action of the manipulating element E. In other words, the metal of the terminal will key into the spaces between the segments in such a way as to resist rotary movement or twisting of the connector on the terminal which is a valuable and important feature, assuring that the terminal assumes permanently its initial set position. On the other hand, this action does not retard quick removal of the connector because when the manipulating element is turned to release the grip, the segments C will back away from the ribs sufficiently to provide enough looseness to permit of the quick attachment of the connector.

Without further description it is thought that the features and advantages of the invention will be readily apparent to those skilled in the art, and it will of course be understood that changes in the form, proportion and minor details of construction may be resorted to, without departing from the spirit of the invention and scope of the appended claims.

I claim:—

1. A battery terminal connector including a hollow sleeve having an inwardly tapered interior wall, a cap rotatably interlocked with said sleeve, battery terminal gripping jaws having outer inclined faces cooperating with the said tapered wall of the sleeve, said jaws each having a cap abutting portion adapted to be engaged by the under side of the cap and also having a shoulder portion, and a headed fastening carried by the under side of the cap

and adapted to engage the shoulder portion of the jaws, to cause said jaws to clamp a battery post, or the like.

2. A battery terminal connector including
5 a hollow sleeve having an inwardly tapered interior wall, a cap rotatably interlocked with said sleeve, battery terminal engaging jaws having outer inclined faces cooperating with said tapered wall of the sleeve, an inwardly
10 directed flange on each jaw, a member at the under side of the cap and having a head whose face next to the cap is spaced farther from the cap than the thickness of the inwardly directed flanges of the jaws thereby
15 to provide space to permit the cap to be readily partially rotated when the connector is engaged with a terminal to start removal of the connector before the head of the fastening engages said inwardly directed flanges of
20 the jaws.

3. A battery terminal connector including a hollow sleeve having a threaded portion and having an inwardly tapered interior wall, a cap rotatably engaging said threaded portion
25 of the sleeve, battery terminal gripping jaws having outer inclined faces cooperating with the said tapered wall of the sleeve, said jaws having cap engaging faces adapted to be engaged by the under side of the cap when the
30 connector is being applied, and also having inwardly directed shoulder portions, and a member having a head carried by the under-side of the cap, the under side of said head adapted to engage with the inwardly directed
35 shoulder portions of the jaws, whereby upon movement of the cap to effect removal of the connector the said head will cause relative movement of the parts to forcibly break the connection between the jaws and the sleeve.

40 In testimony whereof I hereunto affix my signature.

JOSEPH E. FARRELL, Jr.
